UNITED STATES PATENT OFFICE

2,433,596

SKI

Georges E. Carrier, Montreal, Quebec, Canada, assignor to Joseph Robb & Co. Limited, Montreal, Quebec, Canada

Application March 3, 1945, Serial No. 580,891

8 Claims. (Cl. 280—11.13)

1

This invention relates to skis and particularly to sectional skis of the type in which the main or wooden part of the ski is divided transversely into two sections which are detachably secured together in end to end relation when the ski is in use and may be readily separated for convenient storage or transportation.

The primary object of the invention is to provide a sectional ski of the above mentioned type embodying improved means for detachably securing together the two wooden sections so that these sections are more effectively held against accidental separation, or undesirable relative movement in any direction when the ski is in use.

Another object is to provide a sectional ski of the type referred to in which the component parts of the fastening means provided for securing the wooden ski sections together are designed so that the task of joining or separating said sections is greatly simplified and may be quickly and easily accomplished.

Other objects, advantages and characteristic features of the invention will be more readily understood from the following detailed description taken in connection with the accompanying drawings, in which—

Fig. 1 is a fragmentary top plan view of a sectional ski embodying two runner sections joined together in accordance with my invention.

Fig. 2 is a side view of the assembly shown in Fig. 1.

Fig. 3 is a longitudinal sectional view taken substantially along the section line 3—3 of Fig. 1.

As shown in these drawings, the main runner or wooden part of my improved ski is divided transversely into two sections designated 5 and 6.

A rear portion of front section 5 is fitted between depending side flanges 7 of a channel-shaped metal foot plate 8 and extends from the front end to about the middle of said plate. Section 5 is permanently secured to plate 8 by screws 7' or other fastening means and is provided, at its rear end, with a transversely extending horizontal slot 10 which is relatively narrow in the vertical direction and relatively wide or deep in the horizontal direction. The end surface 5a of section 5 which lies above the slot 10 is disposed in a vertical plane while the end surface 5b which lies below said slot is inclined to slope downwardly and rearwardly from the mouth of the slot.

The central portions of the foot plate flanges 7 are rigidly tied together by a relatively wide horizontally disposed connecting web 12 which is welded or otherwise rigidly secured to said

2

flanges. The forward half of the web 12 is fitted in the slot 10 of ski section 5 and serves to effectively hold this ski section and the foot plate 8 against relative tilting movement in a vertical direction. The web 12 may be fitted in the slot 10 so as to assist the fastening screws 7 in taking the rearward thrust of the ski section 5 when the ski is in use. The forward portion of the rear ski section 6 is also fitted between the foot plate flanges 7 so that its forward end abuts the rear end of section 5. The forward end of section 6 is provided with a vertical surface 6a and an inclined surface 6b which fit flatly against the previously mentioned vertical and inclined surfaces provided at the rear end of section 5. The forward end of section 6 is also provided with a transversely extending horizontal slot 15 which corresponds to the previously mentioned slot 10 and receives therein the rear half of the web 12 joining the central portions of the foot plate flanges 7. It will thus be seen that web 12 also serves to prevent relative vertical movement between the foot plate and the forward end of ski section 6.

25 The foot plate 8 is provided, near its rear end, with a vertical hole 20 which registers with a stud-receiving socket 21 provided in the underlying portion of the ski section 6. A metal plate 22 is countersunk in the upper surface of ski section 6 so that it extends across the socket 21. This metal plate is provided with a vertical opening 23 in line with said socket.

35 A removable clamping plate 25 is shown with one end resting on the upper surface of the rear end of the metal foot plate 8 and provided with a stud 26 which extends downwardly through the openings 20 and 23 of foot plate 8 and reinforcing plates 22 and into the socket 21. The other end of the clamping plate 25 is bent downwardly and is shown resting flatly on the upper surface of ski section 6 adjacent the rear end of the foot plate. A hole 30 is provided in an intermediate portion of the clamping plate to receive therethrough a threaded post 31 projecting upwardly from the upper surface of ski section 6. A wing nut 32 is threaded onto the upper end of post 31 and is adapted to be screwed tightly against the upper surface of the clamping plate to thereby securely clamp the rear end of the foot plate 8 between the clamping plate 25 and the ski section 6. In the present instance the threaded post 31 is shown as being constituted by the threaded end of a screw 34 which passes vertically through the ski section 6 and is permanently carried thereby. It will be understood,

however, that other methods of providing the ski section 6 with a threaded post for passage through the opening 30 of clamping plate 25 may be resorted to. While not shown in the present drawings, it will be understood that adjustable toe plates and other elements of ski boot harness may be arranged on or associated with the foot plate 8.

I claim:

1. A sectional ski assembly comprising separable runner sections aligned in end to end relation, a joint-bridging connecting plate overlying and secured to the adjacent ends of the runner sections, side portions depending from the side edges of said plate and overlying the sides of the runner sections, a member extending between and rigidly connected to the depending side portions of said plate, said member being spaced below the lower surface of said plate and being received in mating grooves provided in the opposing end surfaces of the runner sections.

2. A sectional ski assembly comprising separable runner sections aligned in end to end relation, a joint-bridging connecting plate overlying adjacent end portions of the runner sections, fastening means securing said connecting plate to one of said runner sections and means for releasably clamping said connecting plate to the other of said runner sections, said clamping means comprising a threaded post extending upwardly from the last mentioned runner section clear of but in proximity to the adjacent end of the connecting plate, a clamping plate overlying the connecting plate and having an opening through which the threaded post extends and a clamping nut threaded on said post above said clamping plate.

3. A sectional ski assembly as set forth in claim 2, in which the clamping plate is provided with a depending stud extending downwardly through an opening in the connecting plate and into a socket provided in the runner section with which the clamping plate is associated.

4. A sectional ski assembly comprising separable runner sections aligned in end to end relation, a joint-bridging connecting plate overlying the adjacent ends of the runner sections in contact therewith, side flanges extending downwardly from the side edges of said plate and overlying the side edges of the runner sections, fastening means passing downwardly through openings in one end portion of said plate into the underlying runner section, a threaded post projecting upwardly from the other runner section clear of but in close proximity to the adjacent end of said plate, a clamping plate overlying the last mentioned end of the connecting plate and provided

with an opening receiving the threaded post therethrough, and a clamping nut threaded on said post in clamping engagement with the upper surface of the clamping plate whereby the latter is clamped tightly against the upper surface of the connecting plate and the runner section with which the clamping plate is associated.

5. A sectional ski assembly as set forth in claim 4, including a web extending between and connecting the central portions of said flanges, said web being spaced below said plate and fitted in mating grooves provided in the opposing end surfaces of the runner sections.

6. A sectional ski assembly as set forth in claim 4, including a stud extending downwardly from the clamping plate through the connecting plate and into a socket provided in the upper surface of the runner section with which the clamping plate is associated.

7. A sectional ski assembly comprising a connecting plate provided with depending side flanges affording a downwardly opening channel, a pair of separable runner sections aligned in end to end relation with their opposing end portions fitted in said channel, the opposing end surfaces of said runner sections being provided with registering transversely extending grooves, a web extending between and connecting the central portions of said flanges, said web being accommodated in said grooves, and means for securing the end portions of said plate to the underlying runner sections.

8. A sectional ski assembly as set forth in claim 7, in which the end surfaces of the runner sections lying above the grooves are vertical, while the end surfaces lying below the grooves are inclined from the vertical.

GEORGES E. CARRIER.
